ABSTRACT OF THE DISCLOSURE

Automatic sewing method and apparatus in which the fabric workpieces are supported upon a stationary work table having a low frictional surface, the workpiece being slid upon the surface by a movable clamp member which engages down upon the workpiece in a high frictional grip, the clamp member then being driven parallel with the surface while pressing down on the workpiece for moving the workpiece in accordance with the clamp movement. The clamp member is lifted from the workpiece to release it after the sewing operation. Apparatus is shown for automatically lifting the needle and for cutting off and clamping the thread after sewing. In one embodiment, a reciprocating arrester foot operates in timed sequence with the needle to hold small regions of the moving workpiece stationary while the respective stitches are formed, the desired predetermined path of stitches being formed at high speed, and the arrester foot being automatically lifted to inactive position after the sewing operation.

The present invention relates to a fastening method and apparatus and more particularly to a fully automatic sewing method and apparatus for handling the work material and stitching at high speed along any desired predetermined path extending in two dimensions with reference to the work material suitable for automatically fabricating sewn articles, such as garment components, headwear, footwear, and the like in an automation system.

In the past efforts have been made to provide automatic stitching equipment for stitching along a path in two dimension. However, such prior apparatus have involved various serious operating problems and difficulties and have been subject to severe speed and directional change limitations with the result that such prior apparatus have not been suitable for widespread commercial uses. Much of the prior equipment has been restricted to stitching along a straight line path or a substantially straight line as advanced by the intermittent hitching action of a feed dog so that only a limited amount of directional change in the stitching path could be accommodated at the normal stitching speed. In most instances a person was required to handle the work material during stitching or to prepare the work material to place it in holding fixtures or to control the mechanism during stitching, so that the prior mechanism were not actually fully automatic in use and were slow in operation. Prior apparatus which was intended to advance the work material automatically for stitching along a path in two dimensions has operated on the principle of intermittent motion of the whole work material resulting in rapid wear and breakdown of the equipment due to the large inertial forces and vibration arising from the stop and start motion of the whole work and associated equipment, and this stop and start motion has necessitated slow over-all stitching progress.

It is an object of the present invention to overcome the difficulties and problems of the prior art equipment economically and practically to provide a method and apparatus for fully automatically handling the work material and stitching the work material at high speed along any desired predetermined path in two coordinates.

Among the many advantages of the method and apparatus disclosed herein as illustrative of the present invention are those resulting from the fact that the work material as a whole is automatically handled and is propelled continuously by a force which is distributed over a substantial area of the work material near the desired predetermined path to be sewn so as to cause the work as a whole to be in continuous movement during the stitching process. This propelling force acts in a tangential direction to the surface of the work and allows local regions of the work to be arrested briefly while the tangential propelling force applied to the local region increases so as to re-accelerate it when it is released. During the course of the stitching process a small localized region of the work material is briefly arrested while the needle is passed through this particular region. Then this localized region is released to be reaccelerated by the resilience of the material which was stressed in the region and by the increased tangential force being applied to it, so that this local region quickly resumes its movement in synchronism with the work material as a whole. Then the next successive small localized region of the work material is briefly arrested while the needle is passed through this region, after which it is allowed to reaccelerate and to resume its movement in synchronism with the work material as a whole, and so forth.

Advantageously, the present invention enables the stitching operation to start at the edge or at any interior point in an expanse of work material, and the stitching automatically progresses at a high rate of speed along straight lines and around bends and abrupt changes in direction to produce the desired path of stitches extending in two coordinates in a manner suitable for automatically fabricating parts and components of garments and the like in an automation system. Also, the illustrative embodiments of this invention enable the automatically provided stitching patterns to be quickly changed for different production runs to make different articles or components.

As used herein the term "work material" is intended to mean the fabric, cloth, felt, canvas, leather, sheet or like goods upon which the stitching work is performed. This term is intended to include all such types of goods able to accommodate small amounts of distortion in the plane of the goods themselves, regardless of whether the material of the goods is in one piece or multiple pieces, one layer or multiple layers, regardless of whether the goods are woven, non-woven, felted, in sheet form, porous, perforate or imperforate, natural or synthetic or blended.

The term stitching along a path extending in two dimensions (in two coordinates) is intended to mean that the path of the stitches in the work material can be defined with respect to the general plane of the work material in terms of two coordinates, and regardless of whether the work material itself as a whole is planar or non-planar or is subsequently used in a planar or non-planar form. In other words the stitching path may include straight-line segments, curved segments, angles, abrupt changes in directions, spirals, cusps, and the like.

In this specification and in the accompanying drawings are described and shown a fully automatic, high-speed stitching method and apparatus as illustrative embodiments of the present invention, but it is to be understood that these examples are not intended to be exhaustive nor limiting of the invention. These illustrations are given

so as to disclose the invention fully and clearly to those skilled in the art and so that the reader will appreciate how this invention can be adapted and modified in various forms, each as may be best suited for the conditions of a particular usage.

The various objects, aspects and advantages of the present invention will be more fully understood from a consideration of the following description in conjunction with the accompanying drawings, in which:

FIGURE 1 is a perspective view with certain parts schematically shown for illustrating automatic high-speed stitching methods and apparatus embodying the present invention for stitching along a path extending in two coordinates;

FIGURE 2 is a sectional view taken along the line 2—2 of FIGURE 1 and shown on enlarged scale;

Reference to these drawings in detail is made in the following description, and corresponding reference numbers are used to refer to corresponding elements and components throughout the drawings.

GENERAL DESCRIPTION OF HIGH-SPEED AUTOMATIC STITCHING METHOD

FIGURES 1, 2, 2A and 2B show the process of automatically handling and stitching the work material W at high speed in accordance with the present invention. The work material W is illustratively shown, for example, as being a plurality of layers of fabric 21, 22 and 23 in part of a garment. The work W is continuously moving over a work table 24, so as to pass by a reciprocating needle 25 being driven by drive means 27 and this automatic high-speed stitching process produces a line of stitches S extending along a predetermined stitching path in two dimensions in any desired pattern in the work W, for example, such as the path P to be traced by the stitches. The surface of the work table 24 is smooth so as to facilitate sliding of the work thereupon.

In this process a distributed driving force F is continuously applied to a relatively large area of the work material W near the stitching path for continuously moving the work as a whole over the table 24 during the stitching process. Small localized regions R of the work centered about the successive points of needle penetration are very briefly stopped by applying an arresting force in opposition to the applied driving force in the local region, and the needle is passed through the material at the center of the small arrested region of the fabric. When the material being sewn is cloth, then the whole remaining area of the work material W remains in continuous movement even though the small localized region R has very briefly been stopped, and so this local region temporarily lags behind the general movement of the overall area of the work material W. There is a consequent, brief localized distortion of the work which is accommodated by the localized yielding. When the material being sewn is stiff, then the arresting force serves to stop a larger area. As soon as the stitch is completed, the work material is released and accelerates up to speed so as to move ahead into synchronism with its initial movement as a whole.

In order to provide the distributed driving force F for continuously propelling the work material W, in this illustrative embodiment of the invention there is a lightweight, rapidly movable work clamp 26 pressing down through a resilient coupling medium firmly upon the work. This work clamp 26 includes a rigid frame 28 and a resilient coupling medium 30 attached to the frame 28 and positioned between this frame and the work and extending along closely adjacent to the stitching path P. This resilient coupling medium 30 is compliant in compression so as to accommodate changes in thickness of the work material W, for example, such as the transition from the area where the two layers 21 and 22 are present to the area where the third layer 23 also is present, as shown in FIGURES 2, 2A and 2B. This resilient coupling means 30 is also compliant in shear so as to accommodate the distortion which occurs when the work is arrested in its motion with respect to the rigid frame of the clamp, as shown in FIGURES 2A and 2B.

In this example the clamp frame 28 is formed of light-weight metal, such as aluminum having cut-out areas 31 so as to lighten it while maintaining its rigidity, and the resilient coupling medium 30 is a strip of elastic

springy substance such as sponge rubber, extending along closely beside the stitching path P. The edge 32 of the clamp frame 28 is uniformly offset laterally from the stitching path P along the length of this path by a small offset distance, to place the edge 32 of the clamp frame as close as practicable to the needle. The coupling medium 30 projects out slightly beyond the edge 32 so as to extend along even closer to the stitching path P as seen most clearly in FIGURE 1, for reasons as explained further below.

In this illustrative example for purposes of briefly arresting the localized region R of the work material W, there is an arrester foot 34 reciprocated up and down by drive means 35. In this example the arrester foot 34 has a narrow annular bottom surface closely surrounding the needle 25 for engaging the top surface of the work just prior to entry of the needle into the work, as seen in FIGURE 2A. During the formation of a stitch as shown in FIGURE 2B, the point of the needle 25 passes down through a throat opening 36 in the table 24, and the needle thread 37 is engaged by a bobbin thread 38 carried by a bobbin mechanism below the table 24. This bobbin mechanism is of standard type and so it is not described herein in detail. The resulting stitches S as shown in FIGURES 2, 2A, and 2B are of the type identified as Stitch Type 301 in the Federal Standard No. 751 dated Aug. 14, 1959, and entitled "Federal Standard—Stitches, Seams, and Stitchings" which was published by the General Services Administration. This stitch Type 301 is commonly called a "lock stitch," and when this stitch is properly formed or set, the needle thread and the bobbin thread engage each other approximately midway through the thickness of the work material.

The annular bottom surface of the arrester foot 34 holds the local region R of the work firmly down against the table 24 in the immediate vicinity of the throat opening 36. It is possible to use a variety of surfaces underneath this foot 34, depending upon the surface characteristics of the work material. For example, when it is desired to increase the arresting holding effect upon the region R of the work, this may be done by roughening the bottom of the arrester foot 34 by knurling. When it is desired to exert a lower pressure per unit area on the work material beneath the foot 34, then the annular area of the foot may be increased and its arresting effect is provided by using a tough bottom layer of material having a high coefficient of friction such as tough plastic material and the like. As soon as the needle has been withdrawn from the work, then the arrester foot 34 is raised away from the work, releasing the region R for reacceleration as described further below.

The arrester foot 36 also acts as an anti-flagging element. That is, it holds the work down during the upstroke of the needle 25 so as to prevent the friction of the withdrawing needle and thread and the lifting effects of setting the stitch from curling or deflecting upwardly the work material. Any flagging of the work material is undesirable as it prevents the proper setting of the stitch on the upstroke of the needle.

At the conclusion of the desired stitching pattern, the needle 25 is automatically stopped in its top position by a top dead centering mechanism 33, and the arrester foot 34 is lifted and held up higher than during stitching so as to be elevated completely above the clamp 26 by means of an arrester foot lift mechanism 39 also actuating the thread cutter 41, all of which steps are described in detail further below.

During the stitching process the work clamp 26 is moved continuously with relative components of motion in two directions so as to provide the exact direction and rate of motion of the work past the centerline CL (FIGURE 4) of the needle for producing stitching along the desired path P. The work clamp 26 is connected to lightweight, high-speed drive means, generally indicated at 40, for producing the two components of motion. For

clarity of illustration the two components of motion are indicated as being in an X and Y coordinate system.

It is our intention to reduce the mass of the work clamp 26 and its drive mechanism while maintaining a high degree of rigidity so as to move the work material rapidly and accurately to produce a continuous stitching rate throughout the pattern which is equal to the maximum possible stitching rate available from the fastest present day industrial sewing machines, except for a very brief engagement period at the beginning or end of the stitching pattern which amounts to two or three stitches. The illustrative embodiments of the invention produce a stitching rate of 100 stitches per second with a sewing machine having a standard rotary bobbin with a horizontal axis, but it will be appreciated that these methods and apparatus are capable of operating at considerably higher speeds if and when faster sewing machines become available. In the drive system which provides these two desired results of minimum mass and maximum rigidity relative to mass, in this illustrative process the clamp 26 is supported and driven by a hollow, lightweight, spar-like arm 42. Thus, the movement of the work clamp 26 is definable in terms of the angular movement of the arm 42 about its instantaneous center of revolution and the movement of this arm 42 in the direction parallel to its own length, i.e. in terms of angular and radial displacement, and the X and Y components of movement of the work past the centerline of the needle are appropriately provided thereby.

When the stitching pattern has been completed and the thread cut, then the work clamp 26 is quickly moved to the desired delivery point on the work table 24 and is elevated so as to disengage the resilient coupling means 30 from the work to release the completed work at that delivery point. While the work clamp is still elevated it is brought into relative position above a new piece of work material at a work receiving point and then is abruptly lowered onto this new work material at this point and is quickly moved back to the initial position with respect to the needle CL so as to begin the stitching pattern. It is an advantage of this method and apparatus that the position at which the work is received may be the same as the position at which the completed work is delivered, or these positions may be spaced apart, as desired in a particular application.

It is to be appreciated that the handling of the work material during stitching and the stitching process are fully automatically carried out. The new pieces of work material may be delivered manually or automatically to the receiving point on the table and the completed work may be manually or automatically removed from the delivery point on the table. If desired the delivery and receiving points on the table may be closely adjacent, coincident, or widely separated; also, alternate delivery points and pick-up points may be utilized in sequence in successive cycles.

This stitching method and apparatus as described is capable of stitching a pattern at a rate of 100 stitches per second. Ultra-high speed photographs taken at the rate of eight thousand frames per second during the stitching process show that at these very high rates of speed slight deformations of the arm 42 do occur, but fundamentally the arm 42 and clamp frame 28 are in continuous movement while the desired region R of the work is arrested very briefly and then reaccelerated. The reason for mentioning what is seen under ultra-high speed photography is to emphasize the successful operation of this apparatus so that in fact suitable stitching of complex patterns is produced at a rate of 100 stitches per second.

Thus, the amount of mass which is arrested and reaccelerated during and after the formation of a stitch is not significantly greater than the mass of the small localized region R of the work material plus a portion of the adjacent resilient pad 30. Moreover, it is the local spring constant of the work material itself and the re-

silence of the pad 30 which produce the reacceleration of the region R while the work-propelling apparatus is in continuous movement. By virtue of this method the stitching process is automatically carried out continuously at a high rate of speed and a high over-all production rate is provided.

It is to be noted that there are industrial sewing machines which are now in use which have a top speed rating of 100 stitches per second. In these machines the work itself is hand fed by an operator, and the operator slows the machine down when turning corners in the stitching pattern and when making curves and changes in direction. Consequently, the peak speed of 6,000 stitches per minute is obtained only for very brief periods, if at all, and then only during long straight runs or gradual curving portions of the stitching pattern. Thus, the average speed or resultant production rate is far below the peak speed which is only briefly, if at all, obtained.

In the stitching method described above, when used to form a wide variety of useful stitching patterns, we have found that the full speed of 6,000 stitches per minute can actually be maintained throughout the formation of the whole pattern, except for the brief engagement period at the very beginning and very end of the pattern. Moreover, the work material is automatically handled throughout the entire stitching operation.

In the stitching method described above the local region R of the work material is arrested during passage of the needle therethrough, and in this embodiment of the method the region R is arrested by the reciprocating arrester foot 34. We have found that this process works to advantage for a wide variety of types and thicknesses of work material. For example this process works to advantage with thin very compliant work material such as one or two layers of thin skirt cotton and also works to advantage with fairly thick stiff material such as three or four layers of 14-ounce blue denim material, and the like.

We have also found that the local region R of the work material can be arrested by the needle acting solely by itself in entering and passing through the material, as shown in FIGURES 2C, 2D and 2E, if certain precautions are taken and if certain criteria are met. An advantage of operating without the arrester foot 34 is that the method and apparatus are made correspondingly simpler, and hence the apparatus is less expensive and easier to maintain. When the needle alone is used precautions are taken to prevent pressure of the work material from occurring against the side of the needle tending to deflect it against the side of the throat opening 36 and to prevent flagging, as set forth below.

When the arrester foot 34 is omitted, then the resilient and distributed compliant shear force F is applied to the work material quite close to the stitching path to minimize flagging. In this example this is accomplished by extending the edge of the shear compliant coupling medium 30 out from under the edge 32 of the clamp frame 28 so as to be offset from the stitch path P by a very small amount which is sufficient to clear the needle. This resilient medium 30 now serves the function of preventing the work material from flagging upwardly as the stitches are set.

However, the close proximity of the resilient means 30 increases the mass present near the needle and thus tends to raise the side loading on the needle. The exact amount of offset between the edge of the resilient coupling medium 30 and the path P of stitching to be used in a particular case depends upon the upward flexibility of the work material W and also upon its own shear compliance. More flexible work material requires less offset of the medium 30 to prevent flagging, and material with more shear compliance will impose less side-loading upon the needle.

In actual practice these two criteria usually dovetail because more flexible work material is usually also more compliant in shear, and vice versa. If circumstances do

not work out in this way in some cases, then the arrester foot 34 may be used. In the absence of the arrester foot the width of the coupling medium 30 may be reduced below that which is used when the presser foot is present, so as to avoid side loading on the needle. This narrow strip 30 is indicated at N in FIGURES 2C, 2D and 2E, which is narrower than that shown in FIGURES 2, 2A and 2B.

It is desired to avoid stubbing of the arrester foot 34 against the oncoming edge of a layer of work material. This can be accomplished in various ways, but where the problem of stubbing does not occur, then these expedients are not needed. For example, as shown the arrester foot has an upwardly sloping surface surrounding its annular bottom surface. Thus, it does not stub itself against the edge of an approaching additional layer, such as the layer 23 (FIG. 2), but jumps readily upon this oncoming layer, regardless of the direction at which the work approaches the arrester foot. Another way to avoid the stubbing effect is to increase the up-stroke of the foot 34. Where the stitching pattern includes several changes in the number of layers 21, 22 and 23 present, then we have found that the first stitch in an approaching new layer or last stitch in a receding previous layer is made slightly neater in appearance by use of the arrester foot 34, but this difference is usually not significantly noticeable.

In the following description the arrester foot 34 is shown, but it will be appreciated that it and its operating and control apparatus may be omitted when the above criteria are met and the precautions are taken as outlined above in detail.

GENERAL DESCRIPTION OF FULLY AUTOMATIC STITCHING SYSTEM

As shown in FIGURES 3 and 4 the work clamp 26 and arm 42 are driven by a pair of lightweight triangular cam follower levers 44 and 45 driven by a pair of cams 46 and 47 mounted on a common vertical shaft 50. The levers 44 and 45 are disposed on generally opposite sides of the cams 46 and 47 and are arranged and connected so that the lever 44 produces mainly movement of the spar arm 42 in a direction parallel to its own length while the other lever 45 mainly produces angular movement of the arm 42 about the pivot 51. The drive lever 44 has a fixed pivot 52 forming the fulcrum and has an intermediate follower roller 53, so that it is a lever of the third class and produces velocity multiplication at the pivot connection 51 with the spar arm 42. Consequently, the arm 42 is moved in a direction along its length (X direction) at a higher rate of speed than that imparted by the cam 46 to the roller 53.

The drive lever 45 has a cam follower roller 54, a pivot connection 55 to a cross link 56, and an intermediate fixed pivot 57 forming the fulcrum. Thus, it is a lever of the first class and as shown has approximately equal lever arms to provide a velocity at the pivot connection 55 which is approximately equal to that imparted by the cam 47 to the roller 54. This velocity is transferred by the cross link 56 to a pivot connection 58 on the arm 42. The arm 42 itself is a lever of the third class with respect to movement about the pivot 51 imparted by the link 56, and hence there is a movement of the end of the arm 42 perpendicular to its length (Y direction) which is at a higher rate of speed than that imparted by the cam 47 to the roller 54. Advantageously, this arrangement produces velocity multiplication with respect to both coordinates of motion X and Y that are substantially equal. Consequently, the cams 46 and 47 may be of substantially the same over-all size for a wide variety of stitching patterns, thus minimizing the over-all sizes and masses of the levers, link 56 and arm 42 while enabling large pattern areas to be sewn at high speed.

The hollow spar arm 42 is tapered down toward both ends and has a maximum width near the pivot connec-

tion 58 to resist bending stress where the lateral thrusts are imparted. The triangular levers 44 and 45 are hollow, and the cross link 56 is tubular to provide maximum rigidity to mass ratio.

In order to hold the follower rollers 53 and 54 against their respective cams, powerful forces of substantially constant magnitude and directed inwardly generally toward the shaft 50 are applied to each lever at a point adjacent to the follower roller. For example, in this apparatus shown these forces are provided by strip springs 60 and 61 of the type which are self-winding on drums to generate a generally constant tension force regardless of extension. Such strip springs are available commercially under the trade designation "Negator" from the Hunter Spring Company of Lansdale, Pa. The rotating drums of these springs are mounted on the machine frame as shown in FIGURE 4, and the ends of the spring strips are connected to flexible cables 62 and 63 extending upwardly over pulley wheels 64 and 65 and then inwardly and around pulley wheels 66 which are rotatably mounted on the shaft 50. These cables then extend out to anchoring straps 67 on the respective levers 44 and 45.

During rotation of the cams 46 and 47, whenever one of the follower rollers 53 or 54 has just passed over a high spot or lobe on the cam and starts descending, then there is a tendency for the follower roller to try to accelerate the cam as a result of the force produced by the springs described above. The effect of this force would be to take up suddenly any back lash present in the gear train which drives the cam shaft 50, causing an undesirable jerk in the movement of the work clamp 26.

To prevent the cam movement from being influenced by the forces of the follower rollers 53 and 54 bearing against them and thus reacting against back lash in the drive gearing, suitable braking means are provided. For example, there is a large diameter disk caliper brake 69 providing a constant drag force upon the shaft 50 so that any back lash present is always taken up in the same direction with respect to the rotation of the shaft 50.

As shown in FIGURES 3 and 3A the caliper brake 69 includes a large thin metal disk 120 secured to the lower end of the shaft 50. A pair of opposed braking pads 121 and 122 of automobile brake lining material are pressed against opposite surfaces of the perimeter of this large disk. The lower brake element 121 is held by an adjustable screw member and hand wheel 123 mounted in the machine frame. The upper brake element 122 is pressed by a compression spring 124 and is held by an adjustable screw member and hand wheel 125 mounted in the frame. Equal effective pressure is exerted by both brake elements 121 and 122 even though only one spring 124 is used, because the large disk 120 deflects slightly to balance the braking action.

To provide a downward force on the work clamp 26 with a minimum of mass effect on the arm 42, as shown in FIGURE 4, there is a strip spring 68, which is similar to the springs 60 and 61 discussed previously. This tension spring 68 is secured to a long, substantially vertical cable 71 which is connected to the underside of the arm 42 so as to pull downwardly on this arm with relatively constant force regardless of the horizontal position of the arm 42.

When the stitching of the pattern is completed, then the work clamp 26 is moved to a predetermined delivery position at which the arm 42 is raised against the force of the spring 68, thus releasing the completed work from engagement with the resilient compliant means 30 of the clamp 26. For raising the arm 42, lift means 76 (FIGS. 4 and 4a) are provided which engage the arm 42 in the delivery position. In this example the lift means 76 include an electrically controlled pneumatic cylinder 77 having a horizontal leg 81 on its piston rod. This leg element 81 enters a slot 86 in a downwardly projecting bracket 87 on the arm 42. Thus, the arm 42 can be quickly raised.

The fact that the horizontal leg element 81 is in the

slot 86 prevents the arm 42 from continuing to rise when the lift means 76 reaches the end of its stroke, i.e., there is positive stopping and supporting of the work clamp 26 in its upper position, so that its operation can be accurately programmed. After the completed work has been removed a new piece of work can be placed beneath the clamp 26 or, alternatively, the clamp 26 may be moved to another position at which it can be raised by another lift mechanism similar to the means 76 at the delivery station.

For accommodating the elevation of the arm 42 while minimizing the mass involved, the pivot 58 is mounted in a clevis 59, and the arm 42 is vertically slidable along the pivot 58 so that the cross link 56 remains horizontal. Also, the pivot connection 51 has an effective ball and socket arrangement to permit raising of the arm 42. The cross link 56 is held in horizontal position by an upper and a lower pair of saddle rollers 91. These rollers 91 are mounted in a yoke 97 which is pivotally supported at the end of a bracket 99 that is hinged at its other end to the frame so as to permit swinging of the bracket 99 in a horizontal plane to accommodate movement of the cross link 56.

By virtue of the fact that the cross link 56 is always horizontal and is parallel with and mid-way between the planes of the cams 46 and 47, there is clearance for the installation of cams which have large projecting lobes at any point on their periphery, if desired, without conflict with the cross link 56, thus minimizing the required length and mass of the arm 42 and associated drive link and levers 46 and 47.

In this system the needle 25 and arrester foot 34 are connected to a sewing machine 70 having certain conventional parts and many novel elements, as will be described further below. The power for driving the sewing machine 70 at high and at intermediate speeds is supplied from a main drive motor 72 connected by a timing belt 73 to a counter shaft 74 suitably journaled in bearings such as at 75. A main shaft 78 supported by bearings such as 79 parallels the counter shaft 74 and can be driven therefrom through a high-speed timing belt 80 or, alternatively, through an intermediate-speed timing belt 82.

When a high-speed electrically actuated clutch 83 associated with a large sheave 84 is engaged, then the driving path extends through the belt 80 to a smaller sheave 85 on the main shaft 78 so as to produce rotation of the shaft 78 which provides 6,000 stitches per minute. Alternatively, when an intermediate-speed electrically-actuated clutch 88 associated with a large sheave 89 on the main shaft is engaged, then the driving path extends through a small sheave 90 on the counter shaft 74 and through the belt 82 to the larger sheave 89, so as to provide an intermediate stitching rate of 2,400 stitches per minute.

For providing a slow operating speed equivalent to 200 stitches per minute, called "inching speed," both of the clutches 83 and 88 are disengaged, and power is supplied by a slow-speed drive motor 92. This motor 92 has a speed-reducing gear drive 93 and is connected by a timing belt 94 to a sheave 95 attached to an electrically-actuated clutch 96 on the main shaft 78.

The relation of the main shaft 78 always bears a known speed relationship with respect to the rotation of the cam shaft 50, and this known relationship can be changed as desired depending upon the pattern being stitched and the required number of stitches per inch. The main shaft is fastened through a coupling 98 to a speed-reduction gear mechanism 100 having a vertical output shaft 101 connected through a change-gear train 102 to a driven gear 103 on the cam shaft 50. To change the speed relationship between the rotation of the main shaft 78 and the cam shaft 50, the gears in the change-gear train 102 are manually changed.

The cams 46 and 47 are individually removably secured to the shaft 50 each at a fixed angular orientation, for example, by mounting these cams on respective hubs

which are keyed to the shaft 50 and are locked thereto by set screws. The hub 104 of the upper cam 46 is above the cable sheaves 66, and the hub for the lower cam 47 is below them. These cam hubs and these sheaves 66 can all be removed from the upper end of the shaft 50 so as to change the cams 46 and 47 when it is desired to stitch a different pattern.

In order to drive the sewing machine 70 at a known relationship with respect to the cam shaft 50, a drive path is provided, as shown in FIGURE 3 from a sheave 106 on the main shaft 78 to a driven sheave 107 (FIGS. 3, 6, 12 and 13) on the main crank shaft 108 of the sewing machine 70. This drive path to the sewing machine includes a timing belt 110 engaging a sheave 111 on the input shaft 112 of a drive disengage and needle raise and lock-up mechanism 113 (please see also FIGURE 20) having an output shaft 114 with a sheave 115 engaging a timing belt 116 for driving the sheave 107.

In order to control the operation of the system, a plurality of switches 130 (FIG. 4) are mounted beneath a narrow platform 132 which is spaced a substantial distance above the upper cam 46. A switch control drum 134 is removably secured to the upper end of the cam shaft 50, and a plurality of actuators 136 are adjustably secured to the outer surface of the drum at various distances below the upper end of this drum. The switches 130 are also mounted at various distances below the platform 132 so that each individual switch arm 138 is at the same elevation as its respective actuator 136. These actuators are removably secured to the drum, for example by machine screws, enabling them to be set at different positions around the drum, as shown in FIGURE 4. Thus, these actuators operate the various drum switches 130 at predetermined times when the cams 46 and 47 have reached various angular positions in their travel for automatically producing the desired sequence of operations.

As shown in FIGURES 5, 6, 7 and 8, the sewing machine 70 includes a frame 140 having a horizontal arm portion 142 with a sewing head 143. The main crank shaft 108 extends horizontally within the frame portion 142 and is secured to a flywheel 144 (FIGURES 7 and 8) having a crank pin 145 driving a connecting rod 146. The lower end of this connecting rod is joined by a wrist pin 147 to a collar 148 which is rigidly attached to a needle bar 150 for reciprocating this needle bar up and down. The needle 25 is of standard form and is fastened in a socket in the needle bar 150 by conventional means, with the needle thread being fed thereto by the usual guides and adjustable tensioning device 151 (FIG. 8) and a thread take-up arm. The guides and thread take-up arm are omitted from the drawing for clarity of illustration, because they are conventional. FIGURE 8 shows the needle bar 150 in its raised position, this bar being vertically guided by the head frame portion 152 and by a lower bushing. The thread take-up arm is conventional and is included in the sewing head 143, being driven up and down by the main crank shaft 108.

As mentioned previously, there is a conventional bobbin mechanism located beneath the work table 24 near the needle throat opening 36. This bobbin mechanism is of the rotary type having a horizontal axis of rotation and turning at a rate of two rotations for each rotation of the crank shaft 108. This conventional bobbin mechanism is driven from the shaft 108 as shown in FIGURE 5 by means of a set of bevel gears 154 and by a vertical drive shaft 155 within the frame 140.

In order to operate the arrester foot 34, there is an eccentric 156 (FIGURES 5 and 10) secured to the shaft 108 for moving a connecting rod 157 having a pivot connection 158 held by a clamp 159 on a rock arm 160. This rock arm is adjustably attached by a clamp 161 to one end of a horizontal rock shaft 162, and it is the other end of this shaft 162 which serves to drive the arrester foot 34 as will be explained. The adjustable means 161 enables

the length of stroke and the dynamic action of the arrester foot to be varied so as to produce the desired down dwell time of the foot 34 during each stitching cycle for arresting the work region R.

As shown in FIGURE 5, the rock shaft 162 is journaled in bearings 163 and 164. The bearing 163 is mounted in the wall of a housing which is attached to the frame 140 and has a removable cover 166 for preventing the throwing of lubricating oil. The other bearing 164 rests in an L-shaped pillow block 167 which is fastened to the sewing head 143 as by a screw 168. A second rock arm 169 (FIGS. 7 and 8) is held by an adjustable clamp 170 on the end of the shaft 162, and a pivot 171 with a connecting link 172 transfers the reciprocating motion to a pin 173 which is mounted by a clamp 174 on the top end of an arrester foot drive rod 175. Thus, this drive rod 175 is reciprocated vertically through upper and lower slide bearing blocks 176 and 177. The bearing 176 is anchored to the lower end of the L-shaped pillow block 167, and the bearing 177 is fastened by a bracket 178 to the side of the head 143.

When the drive rod 175 moves down, as shown in FIGURE 8, a stroke-adjusting collar 179 affixed to this rod presses down upon one end of a lever 180 which is mounted at its center by a pivot bolt 181 in the head frame portion 152, and so the other end of this lever 180 lifts against a collar 182 on an arrester foot bear 183. Both ends of the lever 180 are bifurcated and straddle the respective rods 175 and 183 to avoid eccentric loading on the rods 175 and 183. In this way the arrester foot bar 183 is lifted against the continuous downward thrust of spring means 184, shown as a compression coil spring surrounding the bar 183 above the lift collar 182 and seated beneath the top part 185 of the head frame portion 152.

When the drive rod 175 is moved upwardly as shown in FIGURE 7, then the spring means 184 serves to press the arrester foot 34 down firmly upon the region R of the work W as described above in connection with FIGURES 1 and 2 so as to arrest the motion of this local region.

As seen clearly in FIGURES 5, 6, 7 and 8, the arrester foot 34 includes an annular portion 190 surrounding an opening 191 (FIGURE 2) concentric with the center line of the needle. By virtue of its round configuration the arrester foot 34 accommodates the close proximity of the edge 32 of the work clamp 26 regardless of the instantaneous direction of movement of the clamp. Thus, the stitching path P can extend in any instantaneous direction through a full 360° with respect to the needle so as to be able to produce any desired stitching pattern in two coordinates.

A semi-cylindrical barrel 192 is integral with the annular foot 34 and extends up along beside and concentric with the needle 25. This barrel 192 has an upper lateral mounting portion 193 which is rigidly but detachably secured to the lower end of the arrester foot bar 183. For example, as shown, the mounting means 193 includes a socket for receiving the lower end of bar 183 which is held by a screw 194. The arrester foot bar 183 is guided by a lower sleeve bearing 196 (FIG. 8) mounted in the lower frame portion 152 and an adjusting screw 195 serves to set the compression of the spring 184.

In order to adjust the timing between the reciprocation of the needle and the action of the arrester foot, there are adjustment means as shown in FIGURES 10 and 10A, accessible by removal of the cover plate 166. These adjustment means include a clamp 186 for securing the eccentric 156 to the shaft 108 and an index disc 187 fastened to the eccentric. An index dial 188 is attached to a mounting on the bevel gear 154 fixed to the shaft 108. The adjustment is made by loosening the clamp 186 so as to turn the eccentric 156, and the adjusted position is shown by an index line 189 on the disc 187 which is adjacent to the marks on the face of the dial 188.

FULLY AUTOMATIC NEEDLE-DRIVE SLOW DOWN, DISENGAGE, RAISE AND LOCK UP

At the completion of the stitching pattern the needle 25 is completely automatically slowed down and then is raised and locked in an upper position. The arrester foot 34 is lifted and the needle thread and bobbin threads are cut off. Then the work clamp 26 (FIGURES 1, 3 and 4) quickly shifts the finished work W over to the delivery point and releases it. This completely automatic sequence of steps and the methods and apparatus for carrying them out are described in detail hereinafter.

When the stitching has almost reached the end of the desired path, then one of the control actuators 136 (FIGURE 4) operates one of the drum switches 130 for engaging the inch-speed clutch 83 (FIGURE 3), and this results in disengaging the high-speed clutch 96 so that the stitching rate drops to 200 stitches per minute for the last two or three stitches in the pattern.

It is noted that the main drive motor 72 and the inching speed motor 92 are continuously rotating, and it is the clutches 83 and 96 which are engaged and disengaged. These are electrically controllable clutches including friction elements which are normally disengaged and become engaged by electromagnetic attraction when energized, such clutches being commercially available. At the moment when the inching-speed clutch 93 is engaged, then the inching-speed motor speed 92 and its associated speed-reduction gear mechanism 93 serve as a brake to slow the speed of the cams 46 and 47 and sewing machine 70 immediately down to inching speed.

At the conclusion of the stitching pattern one of the control drum switches 130 is closed. This particular drum switch is shown in FIGURE 21 as the stop-sewing switch D-5, and through certain control circuits which are explained below, closure of this stop-sewing switch D-5 serves to energize a brake winding 199 of a brake 200 (FIG. 3) on the main shaft 78 and also serves to de-energize the inching clutch winding 96 and to energize a solenoid winding 202 (FIGURE 21) of a needle-drive disengage solenoid air valve (not shown) for abruptly supplying air to a pneumatic cylinder power means 204 (FIGURE 20) so as to retract the piston rod 206 for disengaging a dog clutch 208 in the apparatus 113. This apparatus 113 is shown in FIGURES 3 and 20 and serves the function of disengaging the drive to the needle and of raising the needle bar 150 and locking it up.

As shown in FIGURE 20, the needle-drive disengage apparatus 113 includes the input shaft 112, described before which is journaled in a pair of bearings 210 and 212 mounted on a frame 214. This input shaft 112 is rigidly attached to and terminates within a rotatable tubular clutch element 216 having an axially projecting drive dog 218 forming part of the clutch 208. The output shaft 114, described earlier, is mounted in a bearing 220 on the frame 214 and extends through another bearing 222 having a lock-up dog 224 thereon. The shaft 114 terminates near the element 216, and it has an axially shiftable clutch member 226 splined onto it for controlling its rotation. The shiftable clutch member 226 has recesses at its opposite ends for engaging the respective dogs 218 or 224. When the member 226 is axially shifted so that a recess 228 engages the rotating dog 218, then the shaft 214 and consequently the needle bar 150 (FIGS. 7 and 8) are positively driven, and when the recess 230 engages the fixed dog 224, then the shaft 214 and needle bar 150 are locked stationary.

In order to shift the clutch member 226, a sleeve 232 embraces this member so that the member can rotate within the sleeve and move axially with it. The sleeve 232 is held and moved by a pin 233 engaging a yoke 234 forming one end of a shift lever 236 which is swingably mounted on the frame by a pivot 238 and bracket 240. The other end of this shift lever 236 is coupled to the piston rod 206, while the cylinder 204 is mounted on the frame 214 by a pivot 242 and bracket 244. This sleeve

232 has an extending finger 246 for actuating three switches 248, 250, and 252 at various times. Also this finger 246 prevents rotation of the sleeve 232.

As mentioned previously, at the conclusion of the stitching pattern the cylinder 204 is abruptly supplied with air so as to pull on the shift lever 236, thus disengaging the recess 228 from the dog 218 and biasing the clutch member toward engagement with the lock-up dog 224. If the recess 230 is aligned with the dog 224, then this means that the needle bar 150 (FIGURES 7 and 8) is in its fully raised upper position, in which case the recess 230 engages the dog 224 and locks the needle up. Usually, the brake 200 (FIG. 3) does not stop the needle bar in exactly the upper position, and so the recess 230 is not aligned with and cannot engage the dog 224 even though the power means 204 are exerting a biasing force toward lock-up engagement.

Regardless of whether the clutch member 226 immediately reaches its lock-up position or not, it first

20 moves through the mid position, as shown in FIGURE 20. When in this mid-position the finger 246 closes the switch 250. This switch 250 is shown in FIGURE 21 as the top dead center switch, and through the control circuits to be explained, closure of this switch 250 serves to energize a solenoid winding 253 of a T.D.C. air valve. This valve feeds air abruptly to needle raise and top dead center power means shown in FIGURE 20 as a pneumatic cylinder 254 having a piston rod 256 connected to a slide rod 258 mounted in a slide bearing 260 and having a gear rack 262 engaging a pinion gear 264 secured to an overrunning clutch 266 on the shaft 114. Accordingly, the power means 254 serves to rotate the shaft 114 until the recess 230 does become aligned with the lock-up dog 224 at which moment the clutch member 226 shifts to its lock-up position.

30 In order to assure that the needle bar 150 reaches its upper position quickly and positively, the shaft 114 and the crank shaft 108 of the sewing machine have a speed ratio of $\frac{1}{2}$ to 1 as driven by the timing belt 116, and the clutch member 226 has a pair of recesses 230 spaced 180° apart. Thus, the recess 230 engages the lock dog 224 with a rotation of no more than 180° of the shaft 114, and this stalls the cylinder 254.

When the next piece of work material is positioned beneath the needle, then the power cylinder 204 is operated by one of the drum switches 130 to bias the clutch member 226 toward engagement with the drive dog 218. At this time the input shaft 112 is rotating at inch speed and so the recess 228 in the clutch member 226 engages the dog 218 to begin the stitching again at inch speed. 40 After two or three stitches another drum switch 130 is actuated to deenergize the inch-speed clutch 96 and to reenergize the high-speed clutch 83 for stitching the work at high speed.

50 **FULLY AUTOMATIC RAISING AND LOCK-UP OF ARRESTER FOOT AND THREAD CUT OFF AND CLAMPING**

As soon as the lock-up position of the clutch 208 is reached, the switch 252 (FIG. 20) is operated by the finger 246. This switch 252 includes normally-closed and normally-open contacts 252-A and 252-B, respectively (FIG. 21). Thus, the contacts 252-A become opened, causing the air to be released from the needle raise and top dead center power means 254, which is spring biased so as to return immediately to its initial position. The pinion 264 is mounted on an over-running clutch which permits the rack 258 to return to its initial position, while the shaft 114 remains locked by the dog 224.

60 Also, the finger 246 (FIG. 20) closes the contacts 252-B (FIG. 21) which serve to energize a solenoid winding 268 of an air valve for suddenly supplying air to operate the arrester foot lift power means 270 (FIGURE 6). This arrester foot lift power means 270 is shown in FIGURE 6 as a pneumatic cylinder having its lower end adjustably secured by a pivot bolt 272 in a slot 274 in a chassis plate

276 which is mounted on the side of the sewing machine 70. The chassis plate 276 has an irregular configuration as seen in FIGURE 6 and is secured to the sewing machine frame 240 by attachment screws and studs 277, 279 and 280. (Please see also FIGURE 11.) This chassis plate 276 includes a large central cut out 281, which provides clearance for a certain operating parts as will be explained.

As shown in FIGURE 6, the cylinder 270 has a piston rod 282 which is screwed into a connector block 284 and can be adjusted in effective length by loosening a lock nut 285 seated against this block. A pivot pin 286 connects this block 284 to the end of a lever arm 287 which is adjustably fastened by a pair of bolts 288 and slots 289 to a main control lever plate 290 (see also FIGURE 11). This main control lever 290 is pivotally mounted on the attachment stud 280 by a bushing 291 (FIGURE 11), a sleeve bearing 292 and nut 293.

When air is supplied to the arrester foot lift power cylinder 270, as mentioned above, the piston rod 282 pulls down upon the arm 287, thus the lever 290 swings about the pivot stud 280, as indicated by the arrow 295, raising the outer end 294 (FIGURE 6) of the lever 290. A set screw 296 rests upon this end 294 of the lever 290 and is threaded in a block 298 secured to a second long lever 300 which parallels the lever 290 and is pivotally mounted on a bushing 301 upon the same stud 280, as shown in FIGURE 11. Accordingly, the outer end of the lever 300 is lifted by the set screw 296 as indicated by the arrow 297, and this lever 300 is arranged to lift the arrester foot bar 183 by the lift means shown in FIGURE 7. The end of the lever 300 is connected to a lateral stud member 302 (FIG. 7) which is mounted by screws 299 onto a vertically movable lift slide 303 having a rear shoulder element 304 held by screws 305 for engaging under a collar 306 (FIGURE 8) fastened to the bar 183. This collar 306 includes a guide leg 307 sliding in a vertical slot 308 in the frame 152 for preventing rotation of the arrester foot bar 183.

The lifting action of the slide 303 raises the arrester foot bar 183 above its normal position so that the collar 182 (FIGURE 8) is elevated a substantial distance above the lever 180, this elevation being accommodated by further compression of the spring 184. The slide 303 is suitably guided by a vertical slot 313 engaging a stud 315 secured to the frame 152.

In order to lock the arrester foot up in this elevated position, the long lever 300 is held temporarily by a latching mechanism 309 near the left end of the machine, as seen in FIGURE 6. As shown in FIGURES 6 and 13, the end of the long lever 300 has a shoulder element 310 with an abutment surface 311 which is engaged and held by a latching roller 312 on a pivoted latch 314. This latch 314 is mounted on a hinge pin 316 in the chassis plate 276. A spring 318 urges the latch 314 over toward the left in FIGURE 13 so that the roller 312 is seated upon the abutment surface 311. This latched relationship is shown in dotted outline and by primed reference numbers in FIGURE 13.

Once this latching mechanism 309 has been engaged it holds the arrester foot 34 in its fully elevated position until the sewing machine crank shaft 108 begins to rotate again. As shown in FIGURES 12 and 13 there is a multi-lobed trip element 320 which is secured to the hub 321 of the sheave 107 by a screw 322. As soon as the shaft 108 begins to turn, one of the rounded lobes on this trip element 320 engages an unlatching roller 324 on the latch 314 so as to push the latch back out toward the full-line position shown in FIGURE 13. The latch roller 312 is now out on the slope of the abutment on the shoulder element 310, and so the end of the lever 300 is free to move up as urged by the force of the arrester bar spring 184. Also, this slope of the element 310 cams the latch 314 out farther so that the lobes 320 now miss the roller 324 as these lobes continue to revolve, thus avoiding any impact on this roller 324 during sewing. There is also a spring 326 (FIGURE 6) which is connected between the chassis

plate 276 and a stud 327 on the lever block 298. This spring 326 biases the lever 300 toward its initial position and holds the set screw 296 down firmly against the end 294 of the main lever 290 except when the latch mechanism 309 is engaged.

As described above, when the arrester foot power means 270 (FIG. 6) is energized it swings the lever 290 in the direction of the arrow 295, thus moving the lever 300 which lifts the arrester foot 34 and causes it to be latched in its elevated position. This motion 295 of the lever 290 also produces the cutting of the needle thread 37 and bobbin thread 38, as will be explained below. For cutting the bobbin thread, there is a conventional shear mechanism located below the table 24 near the throat opening 36, and because it is conventional it is not shown herein. This bobbin thread shear mechanism is connected to a lower crank arm 328 (FIG. 11) on a vertical rotatable shaft 329 held in a stand 330 on the table 24. An upper crank arm 332 on this shaft 329 is hinged by a pin 333 to an adjustable-length link 34 (see also FIGURE 6) which is connected by a stud bolt 335 to a slot 336 in the main lever 290. Thus, as the main lever 290 swings in the direction 295 it moves the lower crank arm 328 (FIGURE 11) so as to cut the bobbin thread.

At the time when the lift slide 303 raises the arrester foot to its elevated position, the thread tension device 151 (FIGURE 8) is released from its frictional grip on the needle thread 37. A push rod 337 (FIGURE 8) engages the tension device 151 and is operated by an arm 338 of a bell-crank lever which is pivoted at 329 on the frame 152. The other crank arm 340 is pivoted to a vertical link 341 having an elongated eye 342 arranged to be lifted by upward movement of the slide 303. This lifting motion is transferred by a vertical bracket 343 (FIGURE 7) which is adjustably fastened on the slide 303 by a slot and screw mounting 344. The upper end of this bracket 343 has connecting means 345 engaging in the eye 342 (FIGURE 8). Thus, when the slide 303 is raised, the push rod 337 pushes the outer friction disc 346 of the tensioning device 151 out against the action of a compression spring 348 for freeing the thread from drag.

The following description relates mainly to cutting the needle thread 37 and clamping the cut end so as to be assured that the needle remains properly threaded in readiness for stitching the next work material. As shown in FIGURES 6 and 9 a stud screw 348 fastens a ball joint 349 to the main lever 290. This ball joint 349 forms one end of a link 350 of adjustable length which is similar in construction to the link 334 mentioned above. The intermediate portion of this link 350 includes a threaded rod 351 screwed into the connector 349 and into another ball joint 352, the adjusted length of the link 350 being held by lock nuts 353. A pivot pin 354 joins this link 350 to a crank arm 356 on a horizontal rotatable shaft 358 (FIG. 6) which extends out toward the sewing head 143. This shaft 358 is journaled in a pair of bearings 359 and 360 mounted on the chassis plate 276, and a sprocket 362 (please see also FIG. 7) is mounted on its outer end engaged by a chain 364. The purpose of this sprocket and chain is to swing a thread cutting and clamping mechanism 370 down from its normal rest position, as shown in FIGURE 7, to its active position, as shown in FIGURES 14 and 17, and then to return it to its rest position. FIGURES 14-19 show various details of the needle thread cutting and clamping sequence and will be particularly referred to in the following description.

The thread cutting and clamping mechanism 370 is mounted on a shaft 372 carrying a sprocket 374 (FIG. 7) which is driven by the chain 364. This shaft 372 is journaled in a pair of small bearing blocks 376 and 378 (FIGURE 14) secured to a support plate 380 mounted on the frame 152. The needle thread 37 passes down through a notch 381 in the support 380 and is guided by

an eye 384 in a guide wire 386. This wire 386 is slidably held at one end by a bracket 388 on the support 380, and the other end of this guide wire is bent up at 390 to form a handle by which the wire may be slid out to expose the eye 384 for ease of threading it. This eye 384 when in its operating position guides the thread into a V-shaped cutting notch as explained below.

The mechanism 370 includes a pair of spaced parallel legs 392 and 394 having a fixed shear blade 396 spanned across between their lower ends. This fixed blade 396 has a V-notch 398 with one side of this notch sharpened to form a lower cutting edge 400. A movable shear blade 402 has a pivot connection 404 with the fixed blade 396 and includes a sloping cutting edge 406 in opposed relationship with the fixed edge 400. An end 408 of this movable blade 402 extends out beyond the leg 394 to one side of the mechanism 370 forming an operating arm. This arm 408 is bifurcated as shown in FIGURE 14 and straddles the lower end of a lever 410 which is swingably mounted on the shaft 372 adjacent to the bearing block 378.

As the cutting and clamping mechanism 370 is swung down by the shaft 372 into its lowered position, the V-notch 398 moves toward the needle thread 37 for positioning the thread between the cutting edges 400 and 406. The operating lever 310 abuts against an L-shaped control stop 412 which is adjustably attached to the bearing block 378 by a screw 414 setting in a curved slot 416. The stop 412 holds the operating lever 410 back while the mechanism 370 continues to swing forward. Thus, as shown in FIGURES 17, the shear arm 408 is swung back about the pivot 404 (FIG. 14), causing the cutting edge 406 to approach and then to shear past the fixed edge 400, as shown sequentially in FIGURES 15 and 16. The thread 37 is clamped and becomes cut between the top surface of the movable shear blade 402 and a clamp spring 418 which is secured to the fixed shear blade 396 by a mounting screw 420, a washer 421 and a shim 422. The leading edge of this thread clamp spring 418 is curved up at 424 so as to lead the thread smoothly and positively into clamping relationship beneath the spring. This spring also presses the blades together for shear action.

As shown in FIGURE 18, the end of the thread 37 remains clamped in this manner while the mechanism 370 swings back up. Consequently, a desired predetermined amount of the thread 37 is pulled through the eye of the needle 25 so as to have the proper amount of it extending through the eye of the needle in readiness for starting the next stitching operation. It is to be recalled that the thread tensioning drag 151 (FIG. 8) was released when the lift slide 303 (FIG. 7) raised the arrester foot 34, and so this amount of thread is readily pulled through the eye of the needle.

When the mechanism 370 reaches its rest position again, as shown in FIGURE 19, the operating lever 410 strikes unclamping stop means 426 which returns the lever 410 and movable shear blade 402 to their initial position, thus releasing the cut thread end of proper length as indicated by the dotted line 37'. The stop means 426 is formed by a screw threaded into the support 380 and held in adjustable position by a lock nut 428.

In the preceding discussion it was explained that after the thread cut-off and clamping mechanism 370 reaches its lowest position (FIG. 17) it is swung up again as indicated by the arrow 430 in FIGURE 18. This return movement 430 is initiated as shown in FIGURE 6 by a switch 432 having a roller arm 434 which is deflected by a tab 436 on the extension 287 when the lever 290 reaches the limit of its travel so as to close the switch 432. This switch 432 is shown at the left in FIGURE 21 as the normally open retract and cycle restart switch. When it is closed the result is to deenergize the foot-lift and cut-off solenoid 268 (at the right in FIG. 21) which removes the air supply from the power means 270 (FIGURE 6), returning the lever 290 to its original position.

The return of the lever 290 to its original position causes the sprocket chain 364 to swing the thread cutting and clamping mechanism 370 back up, as discussed above, to its normal rest position (FIGURE 19). When the mechanism 370 reaches the rest position, the end of the needle thread 37 is released as described and also a normally-open, thread-cut-off-completed switch 438 is struck closed by the mechanism 370. This cut-off-completed switch 438 is shown at the left in FIGURE 21, and upon its closure the control circuit serves to energize the high-speed clutch winding 83, thus causing the cams 46 and 47 to turn rapidly so as to move the work clamp 26 quickly over to the point for delivery of the finished piece of work.

As soon as the work clamp 26 has been moved to the delivery point a normally-open cycle and drum switch D-7 (FIG. 21, lower left) is closed, thus disengaging the drive, engaging a brake and energizing a solenoid 442 of an air valve for supplying air to the clamp arm lift cylinder 77 (FIGS. 4 and 4A). Consequently, the clamp 26 is lifted so that the completed work is automatically released.

When the clamp 26 is fully elevated it closes a normally-open switch 444 (FIG. 21, upper left) which causes a set of normally-closed contacts A-1 (FIG. 21, lower left) to be opened. The purpose of opening these contacts is to deenergize the solenoid valve winding 442 because the lift cylinder 77 has now fully raised the clamp 26 so as to release the work, thus ending the whole cycle of operation.

In this illustrative embodiment of the invention the delivery location and supply location are shown as the same. As soon as the next piece of work is positioned at the supply location, a normally open start switch 450 is momentarily closed, for example, as by pushing a thumb button 451. This momentary closure of start switch 450 energizes a holding circuit, explained below, for closing holding contacts B-1, bridged across the start switch and also energizes an air valve solenoid winding 443 for supplying air to drop the horizontal element 81 of the lift cylinder 77 down to its initial position so that the work clamp 26 is thereby engaged down upon the new work material.

As soon as the work clamp is fully down on the new work, a normally-open control switch 452 (FIG. 21, at left) is closed, causing energization of the high-speed clutch winding 83 for rapidly moving the work W over into position beneath the center-line of the needle at the point where the first stitch S is to be made. Just before this first stitch position is reached, an inch-speed control, the drum switch D-3 is momentarily closed, thus de-energizing the high-speed clutch winding 83 and energizing the inch-speed clutch winding 96.

A moment later, now at inching speed, the start sewing drum switch D-4 is momentarily closed for energizing a needle-drive engage air valve solenoid 454, which supplies air to the power cylinder means 204 (FIG. 20) for re-engaging the dog-clutch means 208. As soon as the clutch 208 is re-engaged, the normally-closed switch 248 (FIG. 21, at right) becomes opened for deenergizing the solenoid valve 454.

Immediately upon engagement of the clutch 208, the main crank shaft 108 of the sewing machine 70 begins rotating at inching speed, and the arrester foot latching means 309 (FIGS. 6 and 13) is released by one of the trip lobes 320 so as to drop the arrester foot 34 down into its normal operating range. There is a proper length of thread end through the eye of the needle, and the stitching operation begins at inching speed.

After two or three stitches a high-speed drum switch D-1 is momentarily closed, and the automatic stitching now proceeds at the maximum speed capability of the machine 70, which in this example is 6,000 stitches per minute. This high-speed stitching continues until just two or three stitches before the end of the pattern, at which time the sequence of steps occurs which is discussed at

the introduction of this section, so as to deliver the finished work.

It is noted that this system as shown includes an intermediate speed clutch 96, but in the sequence of operations discussed above this intermediate speed was not used. The reason for including this capability of operating briefly at intermediate speed is to meet the contingency that a user wishes to produce automatically a stitching pattern which includes such large stitches and such abrupt reversals in direction as to make brief periods of intermediate speed operation helpful during the abrupt reversals in direction, when the dynamic loading on the arm 42 and its linkages is the most severe. In our experience in producing a wide variety of useful stitching patterns we have never found that it was desirable or necessary to shift into intermediate speed. All of these patterns were continuously and neatly stitched at high speed, except for the very brief periods at the beginning and at the end of the pattern, which were carried out at inching speed for the purposes of accommodating the engagement and disengagement and lock-up of the needle-drive dog clutch means 208 (FIG. 20).

In the event the user should wish to operate at intermediate speed, then an actuator 136 (FIG. 4) is attached to the drum 134 at the desired position so that the drum switch D-2 is actuated to produce the shift in speed. As soon as the drum switch D-1 is again actuated, then the stitching immediately shifts back into high speed. However, as mentioned above, we have not found that it was either necessary or desirable to use the intermediate speed for a wide variety of useful, typical industrial stitching patterns.

In this apparatus the cam shaft 50 makes one revolution for each complete cycle of operation. There is only one actuator 136 for the high-speed drum switch D-1 (FIG. 20) and two actuators for the inch-speed drum switch D-3. It is noted that more actuators for the high-speed drum switch D-1 could be used if more different speeds are used. High speed is used (1) to move the work from the supply position over into readiness for stitching, (2) during the stitching operation itself, and (3) to deliver the completed work. Inch speed is used (1) during and just prior to the first two or three stitches and (2) at the conclusion of stitching. If intermediate speed is used, then additional actuators 136 would be utilized to shift back into high.

When it is desired automatically to stitch a different pattern, then the work holding clamp 26 is changed to correspond with the new pattern. The cams 46 and 47 are replaced quickly and easily with different cams, and also the drum 134 is replaced with a different drum having the actuators 136 in the desired positions for the new patterns. A keyway on the cam shaft 50 holds the drum and cams in proper alignment to produce the desired pattern and sequence of operation at the correct instants during the whole cycle. It is an advantage of this system that the change-over to produce a different pattern can be conveniently made in a short time.

ELECTRICAL CONTROL SYSTEM

In FIGURE 21 is shown a schematic circuit diagram of the electrical control system as included in the illustrative apparatus described herein. In this schematic circuit diagram the respective drum switch control means 130 (FIG. 4) are schematically represented by contact arms having triangular actuators associated therewith. These seven control switches which are actuated by the drum actuators 136 are indicated by reference numbers such as D-1, D-2, etc.

This electrical control system includes several relays for producing various interrelated actions as explained below. Each of these relays includes a magnet winding and one or more pairs of switch contacts which are operated when the winding is energized. In FIGURE 21 the magnet winding of each relay is indicated by a circle, for example,

such as the winding C of the high-speed relay. The number "5" which appears within the circle C shows the number of pairs of switch contacts which are operated upon energization of the relay winding C, and so forth. A normally-open pair of relay contacts are shown by two adjacent parallel vertical lines; for example, the contacts C-2 are normally open when the relay winding C is not energized. A normally-closed pair of relay contacts are indicated by a diagonal line which crosses the parallel vertical lines; for example, the pair of contacts C-1 are normally closed.

The over-all system includes certain mechanically-actuated control switches which signal the fact that a particular part has reached the desired limit of its travel, for example, such as the cut-off-completed switch 438 (FIG. 19). These mechanically-actuated control switch means are indicated in FIGURE 21 by a switch arm having an associated lever symbol. Those control switch means which are normally open during a sewing operation are drawn as being open, and vice versa.

At the lower right in FIGURE 21 are shown the magnet windings 83, 88, 96, and 199 of the three clutches shown in FIGURE 3 and of the magnet brake 200.

As described in the detailed description, the power means for producing movement of certain mechanical parts of the apparatus include air cylinders. These power means are: work-clamp lift and lower cylinder 77 (FIGS. 4 and 4A); needle-drive engage and disengage cylinder 204 (FIG. 20); top-dead-center cylinder 254 (FIG. 20); and arrester foot lift and thread-cut-off cylinder 270 (FIG. 6). As explained the air flow to respective ones of these cylinders is controlled by one or more solenoid air valves, and the solenoid windings of these air valves are shown at the upper right in FIGURE 21.

The electrical power is supplied from a conventional source such as the power mains 501 and 502, for example, supplying alternating current of 60 cycles at 120 volts, the line 501 being the so-called hot side of the source, and the line 502 being at ground potential. The electrical power for the clutch and brake windings is direct current at 90 volts supplied through a pair of lines 503 and 504. A signal light 505 shows when the D.C. lines are energized, and a control power on-off switch 506-3 completes the circuit. Arc suppressing capacitors 507 are connected across the relay contacts in the circuits to the clutch and brake magnet windings. The switch 506-3 is ganged with the other on-off switches 506-2 and 506-1, as indicated by the dashed arrows, so that they all can be manually closed or opened simultaneously. The electrical system contains suitable fuses 509 at appropriate points as indicated.

During operation a main power switch 508 is closed, causing a signal lamp 510 to become lighted. Next, the manual switches 512 and 514 are closed so as to energize the main motor 72 (FIG. 3) and inch motor 92, respectively. Then, the control power switches 506-1, 506-2 and 506-3 are closed for actuating the control circuits.

When the start switch 450 is closed it energizes the cycle-start relay winding B which controls five pairs of contacts. Contacts B-1 become closed to form a self-holding circuit bridging the switch 450. Contacts B-2 become closed to complete a circuit to the high-speed relay winding C, and the contacts B-3 become opened to interrupt a circuit to the brake control relay-winding H. The pair of contacts B-4 are opened for interrupting the circuit to the cycle-end relay winding Q, and the pair of contacts B-5 are closed for energizing the clamp down valve solenoid 443.

When the clamp is fully down, the switch 452 is closed to complete the circuit to the high-speed clutch relay winding C, controlling five pairs of contacts serving to disengage the previously engaged speeds. The contacts C-1 are opened to deenergize the cycle-start relay winding B, and the contacts C-2 are closed so as to complete a self-

holding circuit to the relay winding C. The pairs of contacts C-3 and C-4 are provided for shutting off the previous speed when entering high speed, and thus they are opened so as to shut off operation of the intermediate speed or inch speed clutches, respectively, when the high speed clutch begins working, and the contacts C-5 (lower right) are now closed for energizing the high-speed clutch winding 83.

As the work clamp nears the position for sewing the first stitch, the inch-speed drum switch D-3 is briefly closed for activating the inch-speed relay winding G, which immediately opens the contacts G-1, serving to shut off operation of both the high and intermediate speed clutches. Also, the self-holding contacts G-2 are closed and the contacts G-3 are closed. These contacts G-3 function as safety interlock means which prevent the sewing operation from starting except when the main drive shaft 78 is turning at the lowest speed, for providing proper operation of the needle drive engage means 208. Also, contacts G-4 (lower right) are closed to supply current to the inch-speed clutch winding 96.

Upon actuation of the start sewing drum switch D-4, the relay winding J is energized through the previously closed contacts G-3, and so the contacts J-1 (upper right) are closed for energizing the solenoid 454 to engage the dog clutch 208 (FIG. 20). As soon as the clutch 208 is engaged the normally-closed switch 248 becomes opened so as to shut off the current in the solenoid 454.

Closure of the high-speed drum switch D-1 energizes the relay winding C for controlling the five pairs of contacts C-1 to C-5 as explained above and produces high speed stitching of the pattern. The inch-speed drum switch D-3 is actuated at the conclusion of the pattern to energize the relay winding G to control the four sets of contacts G-1 to G-4 as explained above.

When the stop sewing drum switch D-5 is actuated, a relay winding K is energized serving to close the contacts K-1 for energizing the brake relay winding H. The contacts K-2 are closed to initiate a sequence of operations associated with thread cut-off, and the contacts K-3 are closed for energizing the solenoid winding 202 to cause disengagement of the needle drive as explained.

It was mentioned that the contacts K-1 were closed to supply current to the brake relay winding H. This opens the contacts H-1 for preventing operation of any of the magnetic clutches and closes the self-holding contacts H-2. Also, the contacts H-3 (lower right) complete the circuit to the brake winding 199.

As the dog clutch 208 moves into neutral position the switch 250 is closed to energize the top dead center relay winding L for closing the contacts L-1 (right center) serving to activate the solenoid 253 for operating the power means 254. When the dog clutch 208 reaches the lock-up position, the normally closed contacts 252-A are opened to disconnect the relay winding L, and the contacts 252-B are simultaneously closed to supply power to the relay winding M. This winding M closes the contacts M-1 (right center) for energizing the solenoid 268 to operate the foot lift and thread cut off power means 270 (FIG. 6).

When the lever 290 has fully moved, the switch 432 (lower left) is closed for energizing the retract relay winding N. The contacts N-1 are closed in order partially to complete a circuit to the high-speed relay C so that the apparatus stands in readiness to shift into high speed as soon as the cut-off operation is completed. The contacts N-2 become opened for disconnecting the brake relay H to release the magnetic brake, and also the contacts N-3 are opened to deenergize the stop-sewing relay K for opening contacts K-1, K-2, and K-3. The contacts N-4 are opened for deenergizing the cut relay M so that the contacts M-1 are opened to disconnect the solenoid 268 with the result that the double acting power means 270 is now energized to return the lever 290 to its original position. A self-holding circuit for relay N is established by closure of contacts N-5, and the purpose of this self-

holding circuit is to prevent re-cycling of the stop, cut, and retract operations. The means for preventing re-cycling of these operations include a drum switch D-6 which is arranged to be opened subsequent to the time when the drum switch D-5 has become opened by movement of the drum away from the stop-sewing position.

In the preceding paragraph it was explained that contacts K-1, K-2, and K-3 become opened when relay N is energized. There is no present additional function performed when contacts K-1 are opened, but the contacts K-2 serve as means to prevent the cut circuit from re-operating during unlocking and re-engagement of the dog clutch 208. The opening of contacts K-3 deactivates the solenoid 202.

When the lever 290 returns to its original position, as discussed two paragraphs above, the sprocket chain 364 returns the cut and clamp mechanism 370 to its rest position. This closes the switch means 438 (upper left) so as to complete the circuit to the high-speed relay C. Rapidly the work clamp 26 delivers the completed work to the delivery position. During this delivery of the completed work the anti-recycle drum switch D-6 is momentarily opened for disconnecting the relay N. When the delivery position is reached, the drum switch D-7 is closed so as to energize the relay winding Q which closes the contacts Q-1 for setting the magnetic brake and closes the contacts Q-2 for activating the solenoid 442 to operate the lift means 76, raising the work clamp. The switch 444 (upper left) becomes closed to actuate the relay A for opening the contacts A-1 (lower left) to cut off the current in coil 442 to complete the cycle of operations and also energizes a signal lamp in series with relay A to indicate that the cycle is completed.

At any time during operation, in case of emergency, it is possible to close a manual stop switch in series with the brake relay winding H. This serves to apply the brake and to disengage the respective drives.

What is claimed is:

1. The method of stitching work material at high speed at a stitching station to produce a path of stitches in a pattern extending in two dimensions in said material comprising the steps of providing a work-guiding surface adjacent to the stitching station and against which the work material is readily slideable, positioning one face of the work material against said work-guiding surface in slideable relationship therewith, engaging the other face of said material by firm frictional engagement, resiliently driving said material by force applied through said firm frictional engagement to said other face causing the material to slide against said work-guiding surface so as to move continuously along said path, intermittently applying an arresting force to regions of said material at said stitching station, said arresting force being in opposition to the initial motion of said material for arresting regions of said material centered about spaced points along said path, passing stitches through said spaced points while the regions are arrested at said stitching station, and after the stitches have been passed therethrough, releasing said material for reacceleration up to the initial motion.

2. The method of stitching work material at high speed at a needle location to produce a path of stitches comprising the steps of providing a surface against which the work material is easily slideable and extending near the needle location, moving a first area of the work material against said surface in sliding relationship therewith, firmly engaging a large area of the work material on the opposite side thereof from said first area and resiliently driving said large area of said material continuously along said path while said first area of the material slides against said surface, intermittently arresting the motion of localized regions of said material centered about successive spaced points along said path when the respective points are at said needle location while continuing the movement of the remainder of said large area, after the respective localized regions have been arrested passing a

stitch through each of said spaced points while the localized regions remain arrested, and thereafter releasing said localized regions to accelerate up to the movement of said large area after each stitch has been formed.

3. The method of automatically stitching an area of work material at a sustained high rate of speed along an irregular line by a stitching needle comprising the steps of providing a work-supporting surface adapted for low-frictional sliding of the work material at a receiving area thereon, engaging the upper face of the work material with high frictional engagement extending along and adjacent to the desired line of stitches, continuously applying a driving force through said high frictional engagement to the work material to slide the work material over said surface for moving the area of work material along a path past the centerline of the needle corresponding with said irregular line, the work material being propelled and controlled in its movement by the difference in the friction against the lower and upper face thereof, intermittently applying an arresting force in opposition to said continuous driving force for very briefly arresting the motion of the material at the centerline of the needle at successive points along said line, inserting the needle through the successive points while they are arrested for forming stitches, and allowing said continuous driving force to re-accelerate the material along said line each time when said arresting force is removed.

4. The method of automatically stitching an area of work material at a sustained high rate of speed along an irregular line in a desired path in the work material comprising the steps of supporting the work material on a smooth surface having low-sliding friction with the work material to facilitate sliding of the lower face of the work material upon said surface, continuously applying tangential driving force to the upper face of the work material by high friction coupling to the upper face of the work material over a substantial area thereof extending near the desired path of stitching for moving the area of work material by sliding the material upon said supporting surface along a path with respect to a sewing station corresponding with said irregular line, the work material being guided and propelled in its movement by low friction sliding of its lower face upon said surface and high friction coupling of the driving force to its upper face intermittently very briefly applying an arresting force in opposition to said tangential driving force for very briefly arresting the motion of the material at the sewing station, forming stitches through the material while arrested at the sewing station, and allowing said tangential driving force to re-accelerate the material along said line when said arresting force is removed.

5. The method of automatically stitching work material at sustained high speed by a needle to produce a path of stitches comprising the steps of continuously applying a driving force to the work material for providing a movement of the work material past a stitching point corresponding with said path, intermittently applying an arresting force to a localized region of the material near to and surrounding said stitching point in opposition to the movement of said material for arresting the material at said point, said driving force continuing while said arresting force is applied, said arresting force being applied to said localized region surrounding the stitching point prior to entry of the needle into the work material at said point for forming a stitch through the arrested material at said point, withdrawing the needle from the work material and thereafter removing said arresting force for allowing said continuous driving force to accelerate the material past said point, again applying said arresting force to the next successive localized region of the material near to and surrounding said stitching point, again said arresting force being applied to said successive localized region prior to entry of the needle into the work material at said point for forming a stitch through the arrested material at said point, again withdrawing the

needle from the work material and thereafter removing said arresting force, and so forth until the path of stitches is completed.

6. Apparatus for stitching work material at high speed along a path of stitches comprising means defining a stitching station, a work-guiding surface extending near said stitching station enabling easy sliding of one face of the work material against said surface for guiding the material, fabric moving means comprising a rigid member in opposed relationship to said surface, driving means for moving said rigid member continuously past said station with motion corresponding to said path, and resilient coupling means secured to said member and positioned between said member and the other face of said material from that sliding against said surface for engaging said other face of the work material, said resilient coupling means engaging the work material with a firm frictional grip extending along said other face near the desired path of stitches for moving said material along said path and for moving said material by sliding said one face against said surface, said resilient coupling means being effectively resilient in compression and in shear and providing a firm frictional grip upon the work material.

7. Apparatus for automatically stitching work material at sustained high speed for producing a desired path of stitches in a pattern of extent in two dimensions comprising means defining a stitching station including a stationary support defining a receiving area for receiving work material to be stitched and said support having a needle throat therein and sewing means including a high speed reciprocating needle adapted to intermittently enter said throat, said stationary support having an upper surface for supporting the work material and which is smooth so as to facilitate sliding of the work material thereupon a rigid frame member for extending near to a top area of the material along beside said desired path, driving means for moving said rigid frame member continuously past said station with motion corresponding to said path, resilient coupling means secured to said frame member and positioned between said member and the top area of the work for engaging said material over a top area thereof extending along beside said path, with a high frictional grip, means for urging said frame member downwardly toward said support for firmly engaging said resilient coupling means upon the work material, means for lifting said frame member against the action of said urging means for disengaging said resilient coupling means from the work material for releasing the work material upon completion of the stitching thereof, said driving means moving said frame member away from said work station to said receiving area for handling the next workpiece, and control means for lowering the resilient coupling means of the clamp member upon the next work material at said receiving area.

8. In an automatic high-speed sewing system including a reciprocating needle for forming stitches in an area of work material, apparatus for moving the work material past the centerline of the reciprocating needle comprising a smooth support providing a low friction surface upon which the work material is slidable, a lightweight movable rigid frame, driving mechanism for moving said frame in a predetermined path adjacent to said support, a resilient coupling medium carried by said frame adjacent to said smooth support adapted to engage the upper surface of the work material in a high friction grip, and means for urging said resilient medium toward said support firmly engaging said resilient coupling medium upon the upper surface of the work material for moving the work material by sliding it along said low friction support surface under control of the high friction grip of said resilient coupling medium carried by said movable frame.

9. Apparatus for automatically stitching work material at sustained high speed for producing a desired path

of stitches in a pattern of extent into two dimensions comprising means defining a stitching station including a smooth support table having a needle throat therein and sewing means including a highspeed reciprocating needle adapted to intermittently enter said throat, a rigid frame member having an area extending near to said table for extending near to the material along beside said desired path, driving means for moving said rigid frame member continuously past said station with motion corresponding to said path, and resilient coupling means secured to said frame member to press the material against said table for propelling said material along beside said path.

10. Apparatus for automatically stitching work material at sustained high speed along a path in a predetermined design comprising means defining a stitching station including a stationary support element having a needle throat therein and sewing means including a reciprocating needle adapted to intermittently enter said throat, a rigid member, driving means for moving said rigid member continuously past said stitching station along said path, and resilient compressible means carried by said member for engaging the work material near said path, said resilient compressible means being effectively resilient in compression and in shear, and intermittent arresting means for briefly arresting the work material at said throat when the needle passes through the work material.

11. In an automatic high-speed sewing system including a reciprocating needle for forming stitches in an area of work material, apparatus for moving the work material past the centerline of the reciprocating needle comprising a smooth support, a light weight rigid frame member, a lightweight rigid arm rigidly secured to said frame member, a first lever pivotally connected to said arm for moving it longitudinally, a second lever, means pivotally connecting said second lever to said arm for moving it laterally, first and second coaxial cams for driving said first and second levers, respectively, drive means for rotating said coaxial cams, a resilient coupling medium carried by said frame adjacent to said smooth support, and means urging said resilient medium toward said support for engaging said coupling medium with work material on said support.

12. In an automatic high-speed sewing system as claimed in claim 11, means for urging said resilient medium toward said support comprising a long tension element connected to said rigid arm pulling said frame member toward said smooth support for maintaining a relatively constant pressure of said resilient coupling medium against the work material regardless of movement of said arm.

13. In an automatic high-speed sewing system as claimed in claim 11, means for pivotally connecting said second lever to said arm comprising a lightweight rigid link having one end pivotally connected to said second lever, means supporting said link for longitudinal and swinging movement, and pivot bearing means connecting the other end of said link to said arm for permitting movement of said arm toward and away from said smooth support independently of said link.

14. An automatic high-speed sewing system as claimed in claim 11 and wherein said first lever is a lever of the third-class pivotally connected to one end of said arm with the other end of said arm secured to said frame for producing velocity multiplication in moving said arm longitudinally, and said second lever is of the first-class and is pivotally connected to said arm at an intermediate point along said arm for producing a corresponding velocity multiplication of said other end of said arm in moving laterally.

15. In a system for automatically stitching work material at sustained high speed including a reciprocating needle for producing a desired path of stitches in a two-dimensional pattern, apparatus for moving the work material past the needle position comprising a movable rigid

5 clamp member having an edge extending along beside and slightly offset from the desired path of stitches, a resilient layer carried by said movable clamp and protruding out beyond said edge more closely adjacent to said path adapted to engage a surface of the work material, means urging said clamp member toward the work material for engaging said resilient layer against the work material in firm frictional engagement, and drive means for moving said clamp member in two directions.

10 16. An automatic sewing system for automatically sewing various two-dimensional patterns in work material comprising a movable member for holding a needle and movable back and forth in a stitching station for sewing work material passed through said station, driving means for driving said needle-holding member back and forth, said driving means having a plurality of different drive speeds, work-moving means for moving the work material through said station, said work-moving means including a removable work-propelling frame having a configuration related to the desired sewing pattern, an arm connected to said frame, a first lever pivotally connected to said arm for moving it longitudinally, a second lever, means pivotally connected said second lever to said arm for moving it laterally, and removable control means driven by said driving means controlling the operation of said first and second levers and for controlling the speed of said driving means.

15 17. An automatic sewing system for automatically sewing various two-dimensional patterns in work material comprising a movable member for holding a needle and movable back and forth in a stitching station for sewing work material passed through said station, driving means for driving said needle-holding member back and forth, said driving means having a plurality of different operating conditions, apparatus for moving the work material through said stitching station including a movable arm and a work-engaging clamp removably secured to said arm and having a shape corresponding generally to the desired sewing pattern, a first lever pivotally connected to said arm for moving it longitudinally, a second lever pivotally connected to an intermediate portion of said arm for moving it laterally, cam means for moving said levers and control means operatively associated with said cam means for controlling the operating condition of said driving means, said control means and cam means being removably connected to said driving means for changing patterns.

20 18. An automatic sewing system as claimed in claim 17 and wherein said cam means includes a pair of coaxial cams and said control means includes a switch-controlling member coaxial with said cams.

25 19. In a system for automatically stitching work material at sustained high speed including sewing means at a station for producing a path of stitches in a two-dimensional pattern, apparatus for automatically handling the work material for moving the work material through the sewing station comprising a work support table upon which the work material is slidable, a movable rigid clamp member having an edge extending along beside and slightly offset from the desired path of stitches, said clamp member being movable toward and away from the table and being movable in two dimensions parallel with the table, a resilient layer carried by said movable clamp along said edge for engaging work material on said support table, means for moving said clamp member toward said table for engaging the work material, drive means for moving said clamp member parallel with the table in two dimensions with movement corresponding with said two-dimensional pattern, and means for moving said clamp member away from the table for releasing the work material after it has been sewn.

30 20. An automatic high-speed sewing system including a sewing machine having a moving needle at a sewing station for forming stitches in an area of work material, a smooth support around said sewing station, a work clamp, resilient pad means carried by said work clamp

and facing said smooth support for engaging work material on said support, a lightweight, rigid movable arm having one end connected to said work clamp, a first lightweight lever having a fixed pivot at one end, a first roller at an intermediate point and a pivot connection at its other end to the opposite end of said arm from said clamp, a second lightweight lever having a fixed pivot at an intermediate point, a second roller at one end and having a link pivotally connected to its other end, said link being pivotally connected to an intermediate point on said arm, first and second cam means engaging said first and second rollers for moving said clamp adjacent to said stitching station, and drive means for driving said cam means.

21. An automatic high-speed sewing system as claimed in claim 20 and wherein said first and second lightweight levers are wider at the center than at their ends and said lightweight arm is wider near the point of connection of said link than at its ends.

22. An automatic high-speed sewing system as claimed in claim 20 and wherein said first and second cam means have a common axis of rotation, and first and second long tension elements connected to said first and second levers, respectively, and extending in toward said axis for holding said first and second rollers in engagement with said cam means.

23. An automatic high-speed sewing system as claimed in claim 22 and including drag braking means for preventing backlash in said cam drive means.

24. An automatic high-speed sewing system including a reciprocable member for reciprocating a needle engaging a thread at a sewing position for forming a line of stitches in an area of work material, controllable drive means for driving said reciprocable member, work handling means including resilient coupling means engageable with the work material for resiliently driving an area of work material past said reciprocating needle, and control means for simultaneously controlling the motion of said work moving means in two dimensions and for controlling said controllable drive.

25. An automatic high-speed sewing system as claimed in claim 24 and wherein said controllable drive means includes a disengageable clutch, and means for raising the reciprocable member for lifting the needle when said clutch is disengaged.

26. An automatic high-speed sewing system as claimed in claim 24 including a reciprocable arrester having a high friction surface intermittently engageable with the work material for intermittently arresting the movement of the work material at said station, lifting means for raising said arrester from its normal operating position, and control means for actuating said lifting means when a line of stitches has been completed.

27. An automatic high-speed sewing system as claimed in claim 24 including an automatic thread clamping and cut-off mechanism and means for actuating said clamping and cut-off mechanism when a line of stitches has been completed.

28. An automatic high-speed sewing system including a reciprocable member carrying a needle adapted to engage a thread at a sewing position for forming a line of stitches in an area of work material, a smooth stationary table for supporting the work material, movable rigid work clamp means having resilient work-engaging means for engaging an area of work material on said table, controllable drive means for driving said reciprocable member and for moving said clamp means, first control means for moving said clamp means toward said table for engaging the work material, second control means for moving said clamp means with respect to the sewing position and said stationary table, third control means for initiating operation of said reciprocable needle member to begin the sewing, fourth control means for stopping operation of said needle member at the end of the line of stitches, fifth control means for moving said clamp means to a delivery

position, and sixth control means for raising said clamp means from the table for releasing the work material.

29. An automatic high-speed sewing system as claimed in claim 28 and including thread clamping means and cut off means for clamping and cutting off the thread at the completion of the line of stitches.

30. An automatic high-speed sewing system as claimed in claim 28 and including a reciprocable arrester for intermittently arresting the movement of the work material at the sewing position, and seventh control means for actuating said arrester during sewing.

31. The method of automatically sewing work material at high speed along a desired path of stitches in the work material by moving the material with respect to a sewing station comprising the steps of providing a work-supporting surface adapted to facilitate sliding of the work material thereupon, positioning the work material at a receiving area thereon, engaging the top surface of the workpiece by a firm frictional engagement extending along adjacent to the desired path of stitches, continuously moving the work material past the sewing station by driving force applied through said firm frictional engagement causing the work material to slide upon said supporting surface as the work material moves past the sewing station, intermittently stopping localized regions of the work material at the sewing station by applying an arresting force opposing said driving force, producing a stitch in each of the arrested localized regions of the work material while the main body of the work material continues to be moved by said driving force, releasing the localized regions of the work material to re-accelerate said regions, thereby to form the desired path of stitches, after said path of stitches has been formed, cutting the thread, moving the work material to a delivery area on said surface by sliding the material along the surface from said sewing station to the delivery area, and disengaging said firm frictional force from the work material at the delivery station for delivering the sewn work material at the delivery area.

32. In a system for automatically stitching work material at sustained high speed including sewing means at a station for producing a path of stitches in a two-dimensional pattern, apparatus for automatically handling the work material for moving the work material through the sewing station comprising a work support table, a movable rigid clamp member having an edge extending along

beside and slightly offset from the desired path of stitches, a resilient layer carried by said movable clamp along said edge for engaging work material on said support table, means for moving said clamp member toward said table

50 for engaging the work material, means for moving said clamp member away from the table for releasing the work material after it has been sewn, said clamp member being carried by a movable arm and said means for moving said clamp member toward the table including a long tension element connected to said arm for pulling said clamp member toward the table, and said means for moving said clamp member away from the table being a lift device which lifts said arm when said arm is in a predetermined position for releasing the work material from the clamp member at said position.

33. In a system for automatically stitching work material at sustained high speed including sewing means at a station for producing a path of stitches in a two-dimensional pattern, apparatus for automatically handling the work material for moving the work material through the sewing station comprising a work support table, a movable rigid clamp member having an edge extending along

65 beside and slightly offset from the desired path of stitches, a resilient layer carried by said movable clamp along said edge for engaging work material on said support table, means for moving said clamp member toward said table for engaging the work material, means for moving said clamp member away from the table for releasing the work material after it has been sewn, said clamp member being carried by a movable arm and said means for moving said

clamp member toward the table including a long tension element connected to said arm for pulling said clamp member toward the table, said means for moving said clamp member away from the table being a lift device which lifts said arm when said arm is in a predetermined position for releasing the work material from the clamp member at said position, and said lift device coupling onto said arm for providing control of the motion thereof.

34. Apparatus for automatically stitching work material at sustained high speed for producing a desired path of stitches in a two-dimensional pattern comprising means defining a stitching station including a stationary support having a needle throat therein and sewing means including a high speed reciprocating needle adapted to intermittently enter said throat, a movable clamp member for moving the work material through said stitching station to produce the desired path of stitches in said material, driving means for continuously moving said clamp member, resilient coupling means secured to said clamp member for engaging said material along beside said path, an arrester foot, reciprocating drive means for moving said arrester foot into engagement with the material for arresting the material to receive the needle, and phase adjusting and stroke adjusting means for adjusting the timing of the motion of said arrester foot with respect to the reciprocation of the needle and for adjusting the stroke of said arrester foot.

35. Apparatus for automatically stitching work material comprising a stationary work table having a low friction surface adapted for sliding movement of fabric workpieces on said surface, stitching means associated with said stationary worktable, a movable work clamp, said work clamp being movable toward and away from said surface and also being movable along said surface, said clamp having means for engaging the workpiece with high frictional grip, means for pressing said clamp down upon the workpiece for engaging the workpiece with high frictional grip, drive means for moving the clamp along a desired path with respect to said surface for sliding the workpiece along said surface, thereby to move the workpiece along a desired path with respect to said stitching means, a reciprocating arrester foot associated with said stitching means, control means for actuating said stitching means and said arrester foot in timed sequence to hold small regions of the moving workpiece stationary while the respective stitches are formed, and means for placing the stitching means and said arrester foot in inactive position upon completion of the desired stitching.

36. Apparatus for automatically stitching work material at high speed for producing a desired path of stitches in a pattern comprising means defining a stitching station, a stationary work support, sewing means including a high speed reciprocable needle adapted to penetrate the work material to form stitches therein, said stationary support having an upper surface upon which the work material is readily slidable, a movable clamp member, said clamp member having a resilient coupling medium on the underneath thereof adapted for engagement upon the work material in high frictional grip thereon, said clamp member being movable down toward said surface, means for moving said clamp member down toward said surface pressing

said resilient coupling medium upon said work material which is upon said surface, said clamp member being movable parallel to said surface, drive means for moving said clamp member parallel to said surface with said resilient coupling medium pressing down on said work material for moving the work material in accordance with the movement of said clamp member, said work material sliding upon said surface during said movement for moving the work material with respect to said stitching station to produce said desired path of stitches.

37. Apparatus for automatically stitching work material as claimed in claim 35 in which the shape of the edge of said movable clamp member conforms with the desired path of the pattern of stitches, said edge of said movable clamp member extending along beside said path, and said resilient coupling medium being located underneath said edge and being in engagement with said work material along beside said path of stitches.

38. Apparatus for automatically handling fabric workpieces for moving them with respect to a work station comprising a work table having a smooth upper surface providing low frictional support of the fabric workpiece enabling them to slide readily thereon, a movable clamp, said clamp being movable toward and away from said surface, said clamp also being movable in a direction parallel to said surface, the bottom of said clamp being adapted to engage thereupon the fabric workpiece in high frictional engagement therewith, means for pressing said clamp down upon a fabric workpiece lying upon said surface, drive means for moving said clamp along a desired path with respect to the work station while said clamp is being pressed down upon the workpiece causing the workpiece to move in accordance with the movement of said clamp, said workpiece being moved by the high frictional engagement of the clamp thereon while the workpiece slides upon said surface, and means for lifting the clamp away from the workpiece after completing the desired path of movement.

39. Apparatus as claimed in claim 37 in which the bottom of said clamp has an elastic springy material thereon engaging the top of the fabric workpiece in high frictional engagement.
